TRANSFORMER BYPASS CIRCUIT

Edward John Diebold, Beverly Hills, Calif., assignor to
I-T-E Circuit Breaker Company, Philadelphia, Pa., a
corporation of Pennsylvania

Application September 17, 1956, Serial No. 610,344

19 Claims. (Cl. 321—48)

My invention relates to a by-pass circuit for contacts and more specifically to a by-pass circuit for the contacts of a contact converter having a novel current limiting means.

Contact converters such as the mechanical rectifiers which are set forth in copending application Serial No. 301,880, filed July 31, 1952, now U.S. Patent No. 2,759,128, issued August 14, 1956, to Otto Jensen, and electromagnetic rectifiers which are set forth in copending application Serial No. 257,398, filed November 20, 1951, now U.S. Patent No. 2,756,380, issued July 24, 1956, to Edward J. Diebold, utilize an electrical contact which is operated between an engaged and disengaged position in synchronism with the input frequency to achieve a unidirectional output to a D-C. load.

It is essential that these contacts close and open on as small a current as possible, if appreciable contact life is to be achieved, and to this end, a commutating reactor, which is a reactor having a relatively low magnetizing current, is connected in series with the contact. In operation, the commutating reactor is unsaturated at the time of contact operation to afford a low current step and thereafter is saturated to present substantially zero impedance to the series connected circuit.

However, even the relatively low magnetizing current of the commutating reactor is too high for a contact to continuously interrupt without eventual contact destruction. Therefore, great efforts have been made in the past to provide so-called pre-excitation circuits for the commutating reactor, which, as may be seen in copending application Serial No. 301,880 operate to compensate for the magnetizing current of the commutating reactor during its unsaturated interval and thereby substantially decrease the current through the contact during the period of unsaturation.

In addition to the pre-excitation circuit, which achieves almost perfect compensation, contacts of devices such as contact converters are provided with a by-pass circuit which is also known as a spark extinguisher circuit.

The by-pass circuit is operative to act as a shunt across the contact during contact disengagement so that the residual current carried by the contact during disengagement may be shunted into the by-pass circuit. Clearly, it is important that the by-pass circuit presents a low impedance and particularly a low inductance to the residual current at the time of contact disengagement to prevent the appearance of a high voltage drop across the separating contacts.

However, when the contact is open and reverse voltage appears across the open contact, a low impedance by-pass circuit would short-circuit the contact. Hence, it is essential that for this condition, the by-pass circuit has a very high impedance.

Hence, a by-pass circuit must serve the dual function of having a low impedance while the contact disengages and a very high impedance after disengagement.

By-pass circuits of this type may be seen in copending application Serial No. 490,319, filed February 24, 1955,

2

wherein a reactor is utilized to maintain a current in the by-pass circuit. While this circuit is an effective one, the size of the required reactor may become economically prohibitive. Furthermore, the space and heat dissipation requirement of such reactors poses other practical problems.

The principle of my invention is to provide a by-pass circuit wherein magnetizing current of the main commutating reactor can flow in parallel with a series connection of the contact and an auxiliary commutating reactor which is constructed as to have a substantially negligible magnetizing current, this by-pass circuit consisting of the A-C. terminals of a bridge-type single-phase semiconductor rectifier, the D-C. side of which is connected to a transformer secondary winding and a resistor. A by-pass circuit consisting of a bridge-type rectifier with a D-C. load circuit consisting of a secondary transformer winding and a resistor in series in accordance with my invention will have a high impedance whenever the transformer voltage is in opposition to the normal rectifier output current, or when the rectifier output current is equal or larger than its output current.

When the input to the by-pass rectifier (its A-C. terminals) carries a current which is lower than the current supplied by the transformer winding through the resistor to the output side of the rectifier, the impedance is very low. In the above case, the high impedance value is equal to the resistance of the resistor, whereas the low impedance value is given by the differential resistance of the semi-conductor cells which may be very low.

By connecting the by-pass circuit in parallel with the series connected auxiliary commutating reactor and contact, it is seen that a very low voltage will appear across the auxiliary commutating reactor prior to contact disengagement since at this time the by-pass circuit impedance is very low. Hence, the auxiliary commutating reactor will be demagnetized very slowly and its magnetizing current will substantially be at the static value which can be very easily compensated.

Furthermore, the voltage appearing in this auxiliary commutating reactor is always the same and can be made to have a small constant value.

It is of importance to note that my novel by-pass circuit can be applied in the absence of complex pre-excitation circuits or straightener circuits of the type set forth in U.S. Patent No. 2,860,301, issued November 11, 1958, for the main commutating reactor.

Furthermore, my novel by-pass circuit may be used without interfering with the operation of their auxiliary circuits such as the flux reversal circuit shown in copending application Serial No. 423,358, filed April 15, 1954, now Patent No. 2,860,301.

Accordingly, a primary object of my invention is to provide a by-pass circuit for electrical contacts.

Another object of my invention is to provide a by-pass circuit for the contacts of a contact rectifier.

Still another object of my invention is to provide a by-pass circuit for electrical contacts utilizing a series connection in a commutating reactor and the contact connected in parallel with a circuit having a current flowing therethrough, this by-pass circuit comprising a semi-conductor rectifier having A-C. terminals connected in series with the by-pass current and D-C. terminals connected in series with a transformer winding and a resistor.

Yet another object of my invention is to connect an auxiliary commutating reactor in series with an electrical contact and to then provide a parallel circuit including a rectifier having current flowing therethrough whereby the auxiliary commutating reactor forces current which would normally flow through the contact to flow through the parallel circuit to buck down the by-pass rectifier current.

These and other objects of my invention will become apparent from the following description when taken in conjunction with the drawings in which:

Figure 1 shows a schematic diagram of a three-phase mechanical rectifier to which my novel by-pass circuit may be applied.

Figure 2 shows an embodiment of my novel invention when taken in conjunction with one phase of the circuit of Figure 1.

Figure 3 shows the rectifier used in the by-pass circuit of Figure 2 in conjunction with its operating voltages and currents.

Figure 4 is a graphical representation of the operation of the by-pass circuit rectifier of Figure 2.

Figures 5a through 5f show the voltage and current variations as a function of time for the by-pass circuit of Figure 2.

Figures 6a through 6d show the voltage and current variations as a function of time for the operation of the by-pass circuit of Figure 2, when taken in conjunction with its flux reversal circuit.

Figures 7a and 7b show a possible simplification in the construction of the circuit of Figure 2.

Figures 8a and 8b show the simplification of the circuit of Figures 7a and 7b in conjunction with the flux reversal circuit.

Figure 9 shows the application of my novel invention to a complete six-phase rectifier circuit.

Referring now to Figure 1, there is seen one possible basic circuit for a three-phase contact rectifier. Phase A of the device is seen to comprise commutating reactors 11 and 12 and contacts 15 and 16, wherein the commutating reactor 11 and contact 15 are connected in series with the positive output terminal 17 and commutating reactor 12 and contact 16 are connected in series with the negative output terminal 18.

The phases identified as phases B and C in Figure 1 are constructed in an identical manner to phase A.

Further details on the construction of the commutating reactors 11 and 12 and the contact devices 15 and 16 and the operation thereof, may be had with reference to copending application Serial No. 301,880 as well as co-pending application Serial No. 423,358.

Figure 2 shows phase A of Figure 1 with the application of my novel by-pass circuit.

The commutating reactors 11 and 12 are more specifically shown as comprising cores 23 and 24 respectively which are constructed of a highly saturable type material. Cores 23 and 24 may be provided with pre-excitation windings 25 and 26 which are energized from a source of pre-excitation energization 27. They are further provided with flux reversal windings 28 and 29 which serve to operate as a regulating means for the rectifier, these windings 28 and 29 being energized by a flux reversal circuit which will be more completely described herein-after.

It is then seen that the main windings 21 and 22 of the commutating reactors 11 and 12 are connected in series with the contacts 15 and 16 of the rectifier which are driven into and out of engagement with one another by an operating means which may be seen with reference to copending application Serial No. 301,880 above mentioned.

The by-pass circuit of my novel invention comprises the components shown generally at 13 and 19 in the phase containing commutating reactor 11 and the components shown generally at 14 and 20 of the phase containing the commutating reactor 12. More specifically, components 13 and 14 are saturable reactors having cores 32 and 33 respectively which have windings 30, 34 and 31, 35 respectively. Saturable reactors 13 and 14 are then constructed in such a manner that the magnetizing current of the windings 30 and 31 is smaller than the magnetizing current of the corresponding commutating reactor windings 21 and 22 of the commutating reactors 11 and 12.

Component 19 is seen to be a full wave bridge connected rectifier containing diode elements 37, 38, 39 and 40 which may be of the germanium type. Similarly, component 20 is a rectifier bridge of the same type as the bridge 19 and contains the rectifier elements 41, 42, 43 and 44.

The A.-C. terminals of each of the bridge rectifiers 19 and 20 are then seen to be connected in parallel with the series connection of the saturable reactor windings 30 and 31 respectively and the contacts 15 and 16 respectively. The D.C. terminals of each of the rectifiers 19 and 20 are then energized by the output of the secondary windings 47 and 48 of transformer 51 which is energized at the terminals 52 and 53 of the primary winding 50. Resistors 45 and 46 are provided in series with each of the respective rectifier circuits coming from the secondary windings 47 and 48.

In order to describe the operation of the circuit of Figure 2, component 19 is repeated in Figure 3. In each branch of the bridge 19 of Figure 3 a current marked i_5 , i_6 , i_7 and i_8 flows through the diode elements 37, 40, 38 and 39 respectively. Similarly, each rectifier element 37, 40 and 38 and 39 has a voltage drop shown as a voltage e_5 , e_6 , e_7 and e_8 respectively.

A current i_3 is then seen to flow into the junction between the rectifiers 37 and 38 and flows away from the junction between the rectifiers 39 and 40, while another current i_4 flows into the bridge at the junction between the rectifiers 37 and 39 and flows out of the bridge at the junction between the rectifiers 38 and 40. The importance of these outside currents i_3 and i_4 can be seen in Figure 2 where the current i_3 is the magnetizing current of the commutating reactor 11 which by-passes the contact 15. The current i_4 is provided by the transformer winding 48 and flows in series with the bridge 19 and resistor 45.

It is important to note that the two currents i_3 and i_4 are provided by different sources and both flow through the same rectifier circuit. More precisely, the current i_4 is a direct current flowing through the two branches of the rectifier 19 and is independent of the current i_3 because a direct current can flow through a rectifier in the forward direction in any magnitude and is not hampered by the fact that there is a rectifier in the circuit. On the other hand, the current i_4 is provided from a voltage impressed from the outside and can flow through the rectifier 19 according to the impedance of its D.-C. branch which is given mainly by the resistor 45 and the voltage impressed on the winding 48 of the transformer 51.

Figure 3 also shows five equations (Equations 1 through 5) connecting the voltages and the current e_3 through e_8 and i_3 through i_8 , these equations being derived from a simple application of Kirchhoff's laws.

Figure 4 plots Equations 1-5 of Figure 3 with respect to a typical diode characteristic of the diodes used in rectifier 19 where the current values are plotted on the ordinate and voltage values are plotted on the abscissa.

From the voltages and currents shown in Figure 4, it is seen that the overall voltage drop e_3 in the direction of the by-pass current is the relatively small voltage difference between the voltages e_7 or e_8 and e_5 or e_6 as may be seen from Equation 3 of Figure 3.

On the other hand, the voltage e_4 is a much larger voltage drop. The rectifier circuit therefore has the property that one circuit, which is the one supplied by the transformer 51 supplies the voltage drop for the current i_3 which comes from another circuit. If the voltage drop in the circuit is to be further reduced and the current i_3 is approximately the same value, it is possible to select the diodes accordingly in such a way that the diodes 38 and 39 which are subjected to the larger current i_7 and i_8 have a lesser voltage drop than the diodes 37 and 40. Practically, this can be easily done because the diodes 38 and 39 have to carry a larger current and can therefore be larger area diodes whereas the diodes 37 and 40 which carry only a small current can be small area

diodes. This deliberate mismatch will provide an even smaller voltage drop e_3 over the whole by-pass rectifier.

It is to be noted that the purpose of Figure 4 is merely to effect a solution of Equations 1 through 5 given in Figure 3 for the voltage e_3 . That is to say, it is necessary to resort to graphical means for a solution of this type in view of the non-linear nature of the forward voltage drop characteristic of the rectifier 19.

The flux reversal circuit shown in Figure 2 comprises the flux reversal windings 28 and 29 of the commutating reactors 11 and 12, transductors 54 and 55, a power source including the transformer 65 which is energized at terminals 66-67 and a biasing means which is energized from the terminal 64.

More specifically, the transformer 65 is connected in such a manner as to be connected in series with the flux reversal winding 28, winding 58 of transductor 54, and rectifier 62 while a parallel circuit is provided which includes the flux reversal winding 29, transductor winding 59 and diode 63. The connection of diodes 62 and 63 permits current to flow alternately through one branch or the other branch of the circuit.

The transductors 54 and 55 which are shown as having cores of saturable type material 56 and 57 respectively are provided with biasing windings 60 and 61 which are energized by the biasing source 64.

The operation of this circuit is as follows:

When the potential of the source 65 is in a direction to pass current through the diode 62, it is seen that the volt seconds impressed across the winding 28 will be determined by the time at which the reactor 54 saturates, which in turn is dependent upon the biasing at the biasing winding 60. In the reverse direction, that is when the source 65 reverses, the reversal of flux in the core 54 is dependent upon the semi-conductor 62 as well as the level of the bias in the biasing winding 60. The reverse voltage of transformer 65 appears on winding 58 as long as the current is in a direction of the diode 62. As soon as this current wants to reverse, then the voltage of the transformer 65 appears on the diode 62.

The point of the transition of the voltage from the winding 58 to the diode 62 is given by the bias current flowing in winding 60. The amount of voltage which appeared during the reverse cycle on the winding 58, however, determines the amount of flux which was reset in this reactor core 56, which in turn must be shifted into the opposite direction during the next successive positive cycle of the voltage in transformer 65. Hence, the flux in the core 56 must first be reversed by means of voltage appearing on the winding 58 before the remainder of the voltage can appear on winding 28.

This system of flux reversal has the advantage that the control current provided by the source 64 is a direct current and that this direct current is of very small magnitude and can be provided by a source of extremely low voltage. On the other hand, the power output of the flux reversal circuit itself is provided by the power coming from the transformer 65. Therefore, a high amplification is obtained from the power source 64 to the power output into the windings 28 and 29. Another stage of power amplification then occurs between the input of the commutating reactor, that is the flux reversal windings 28 and 29, to the output of the mechanical rectifier on the terminals 17 and 18.

Figures 5a through 5f specifically illustrate the manner in which the circuit of Figure 2 operates, wherein Figure 5a shows the voltage of the three phases, e_a , e_b and e_c of Figure 1. Since Figure 2 shows phase A of the circuit of Figure 1, the voltage e_a of Figure 5a is the voltage appearing across the circuit.

Figure 5b shows the commutating voltage e_b minus e_a appearing between point A and the positive terminal 17 of Figure 2. This commutating voltage appears only during the time that commutation actually occurs between the phase A and B. For this reason, the com-

mutating voltage is shown only as a dotted line because for the most of the cycle the contact 15 is open and this commutating voltage appears across the contact 15.

During the break step or contact disengagement interval, the commutating voltage appears on the commutating reactor 11 and is shown as e_{11} in the Figure 5b. Applying a voltage like e_{11} to the commutating reactor winding 21 will cause a certain magnetizing current. Assuming that there is no pre-excitation current in the winding 25 and that during this time the current through the winding 28 is zero, the current flowing through the winding 21 will be given by the magnetizing current required to magnetize the core 23. This current is shown as i_{11} in Figure 5b. The current i_{11} is a typical magnetizing current of a saturable core reactor containing a nickel iron core having a so-called square hysteresis loop. The current is, however, variable enough during this step to be hard to compensate by means of a constant current.

Figure 5c shows two heavy lines i_1 and i_s which show the magnetizing current of the commutating reactor for the longest or earliest break step i_1 and the shortest or latest break step i_s . The actual position of this step will be determined by the voltage regulation of the rectifier.

In the normal operation of the mechanical rectifier, the steps will never be longer or earlier or shorter or later than these two extreme values. The current i_s is always larger in magnitude than the current i_1 because it is caused by a higher voltage and a faster magnetization. The values shown in Figure 5c however show that there is only a small difference in the actual current values.

The dotted lines around the two current curves of Figure 5c are the voltage curves which are taken from the dotted voltage lines in Figure 5b. They are marked as e_1 for the commutating voltage during the break step on the commutating reactor during the longest break step and e_s as the commutating voltage during the break step of the shortest break step.

The solid line in Figure 5c marked as i_4 is the current which is provided from the outside current source of the transformer 51 into the by-pass circuit of Figure 2. The current i_4 of Figure 5c is deliberately made larger than the largest magnetizing current available in the full range between the longest and the lowest step to the shortest and highest step. For this reason, Figure 5c shows the two extreme cases simultaneously and is not a physical representation of one process.

Figure 5b shows an example of one particular step current i_{11} which corresponds to the operation shown in Figures 5d-5f.

It was seen in Figures 3 and 4 that the by-pass rectifier 19 will have a very low voltage drop as long as the current i_3 is smaller than the current i_4 . From Figure 5c, it is seen that the current i_1 or i_s is the current provided by the commutating reactor which flows either through the contact 15 or the by-pass rectifier 19. If the current through contact 15 is to be held at zero, then the full current of the commutating reactor i_{11} must flow through the by-pass rectifier 19. As seen in Figure 5c this current i_{11} is always lower than the current i_4 and the condition described in Figures 3 and 4 is met. Hence, by providing a current i_4 which has the shape shown in Figure 5c, the conditions of the by-pass circuits will be fully met and the voltage e_3 which is the voltage drop off the by-pass circuit will be extremely small as demonstrated in Figure 4. In a practical case, if the current i_3 has a value of three amperes as shown in Figure 4, the voltage drop e_3 is equal to .34 volt.

Figure 5d shows the voltage e_{15} appearing across the contact 15 and, as a dotted line, the voltage e_{48} which is the voltage induced in the winding 48 of transformer 51. The voltage appearing on resistor 45 therefore, will be the rectifier voltage e_{15} plus the voltage e_{48} rectified. Adding these two voltages gives the curve e_{45} of Figure

5e which is the voltage appearing on the resistor 45. Figure 5e also shows as a dotted line the negative value of this voltage which does not appear on the resistor but appears on the rectifier 19.

It may be noted that the voltage e_{45} of Figure 5e is also a measure of the current i_4 because of the resistive nature of the resistor 45 and the solid line of Figure 5e therefore also shows the current i_4 .

Figure 5f finally shows the division of currents between the contact, parallel circuit and commutating reactor. The solid line i_3 is the current flowing through the by-pass circuit and is actually the current which should be taken away from the contact 15. The dotted line $i_5 + i_6$ in Figure 5f is an internal current in the by-pass circuit which has no equivalent on the outside. The sum of the current i_3 plus the dotted current $i_5 + i_6$ is equal to the current i_4 as may be seen from Equation 1 of Figure 3. Hence, i_3 will be smaller than the current i_4 , if $i_5 + i_6$ is different from zero during the whole of the break step as shown in Figure 5f and the by-pass circuit will operate as is desired.

If the by-pass circuit of Figure 2 operates as described in Figures 5a-5f, then its voltage drop e_3 of Figure 4 will be extremely small. Having a very small voltage drop on the by-pass circuit 19 means that during the break step an extremely small voltage drop appears on the winding 30 of the auxiliary commutating reactor 13. This means that a voltage of 400 to 500 volts may appear on the winding 21 of commutating reactor 11 while a voltage of only approximately $\frac{1}{2}$ of a volt will appear on the winding 30.

It is interesting to note that this low voltage is practically independent of the time of operation of the rectifier because this voltage is only caused by the drop of the voltage on the rectifiers on the bridge 19 by means of the current which can vary in the range between i_1 and i_2 shown in Figure 5c. Because these currents are inherently approximately constant, the voltage drop is subject to very small variation as may be seen in Figure 4. Hence, the voltage appearing on the coil 30 of the auxiliary commutating reactor 13 is almost constant and very small.

Therefore, the commutating reactor 13 operates nearly on its static hysteresis loop and is magnetized very slowly, whereby its magnetizing current is extremely small and constant. Having but a small and constant magnetizing current, it is easy to compensate the reactor 32 by means of a direct current flowing through the winding 34 provided by the source 36. Assuming that this very simple compensation is provided, the residual current i_2 shown by the dot-dash line in Figure 5f through the winding 30, which is the current that must be broken by the contact, is practically zero. Furthermore, since this current is obtained as a difference between an almost static magnetizing current in a small commutating reactor subjected to a small and almost constant voltage, which does not change with the load condition of the rectifier or the impressed voltage on the rectifier, the compensation of this current can be made almost perfect.

It is also seen that when the contact 15 of Figure 2 opens, the recovery voltage across the contact is only that voltage drop due to the flow of by-pass circuit current. It was seen in Figures 5a-5f that the whole of this by-pass current flows through the by-pass circuit causing only a negligibly small voltage drop of a fraction of a volt. This small voltage drop is the full recovery voltage across the contact and a higher recovery voltage across the contact can not occur as long as the break step lasts.

My novel by-pass circuit, therefore, allows interruption of the contact of a contact rectifier under substantially zero voltage and current conditions. This compensation will be afforded under any condition of load input voltage or phase control because it is independent of the magnitude of the magnetizing current and of the

speed of magnetization in the main commutating reactor and dependent only because on an auxiliary commutating reactor which is subjected to a load condition of an auxiliary rectifier.

Figures 6a-6d show the operation of the flux reversal circuit of Figure 2 and demonstrates the manner in which my novel by-pass circuit cooperates with the flux reversal circuit.

In Figure 6a the phase voltages of Figure 5a are repeated for convenience and Figure 6b shows the current i_1 which flows through the commutating reactor winding 21.

Figure 6c shows the voltage e_{65} impressed by the flux reversal transformer 65 upon the flux reversal circuit consisting of the flux reversal winding 28, transductor 54 and the semi-conductor 62. In the first negative half wave of voltage e_{65} the diode 62 blocks. However, since there is a direct current flowing through the winding 60 of transductor 54, the current through winding 58 is not quite zero and the voltage e_{58} appears on the winding 58 until the current i_{28} has died down to zero. This current is shown as i_{28} , a dotted line in Figure 6d. The dotted line $i_{28} \times 100$ shows the same current magnified one hundred times, showing the effects of the small magnetizing current of the saturable core 56. Therefore, in the first part of the negative half-wave, the voltage e_{58} appears as e_{58} of Figure 6c on the winding of the transductor 54.

In the latter part of the cycle, after the vertical dotted line in Figure 6c, the transductor 54 cannot absorb any more voltage because its magnetizing current is larger than the negative bias in the winding 60, i.e., i_{28} would become negative except for diode 62, which means that now all the voltage of the transformer 65 appears on the diode 62 as is shown by the voltage e_{62} in Figure 6c.

In the successive positive half-cycle, the voltage e_{65} is again applied to the same components but almost no positive current i_{28} can flow until the flux of the transductor 54 has been returned to the positive direction as shown in Figure 6d. Therefore, the voltage e_{58} now appears in the opposite direction on transductor 54 as is shown as the positive shaded area of Figure 6c.

When the transductor core 56 saturates in the forward direction, the remaining voltage of the transformer 65 applies itself to the winding 28 of the commutating reactor because the diode 62 cannot absorb any voltage in this direction. A part of this positive voltage also is absorbed by the resistive voltage drop of all the components because now a substantial current flows in a forward direction, this resistive voltage drop being shown as Δe in Figure 6c. In a practical case, however, this resistive voltage drop is very small and may be neglected.

Hence, the flux of the commutating reactor core 23 is reversed by a predetermined amount by the voltage e_{28} of Figure 6c and determines the amount of flux which is available for the next step and therefore controls the output voltage of the mechanical rectifier.

Figure 6d shows the flux reversal current i_{28} in the winding 28. The current i_{28} , shown as a dotted line, is the actual magnetization current of the commutating reactor core during the flux reversal interval. This current is a step current occurring when a variable voltage is impressed, such as a voltage e_{28} shown in Figure 6c. The commutating reactor under these circumstances, however, is a transformer because the voltage e_{28} which appears on the winding 28 is transformed into the winding 21 and therefore appears as an additional voltage to the reverse voltage of the rectifier as well as on the by-pass circuit which contains the resistor 45. This may be seen in Figure 5e where the voltage e_{45} contains a component due to the flux reversal shown as a sharp peak towards the end of the wave.

This peak is a direct effect of the flux reversal and causes a resistive current in the resistor 45. An additional current i_{45} must therefore be supplied by the flux reversal circuit as is shown in Figure 6d by a dot-dash line. The total flux reversal current then assumes the

shape of i_{28} shown as a solid line in Figure 6d. This total flux reversal current therefore is the sum of a magnetizing current and a resistive current.

Therefore, the operation shown in Figures 6a-6d is the operation of a magnetic amplifier reversing the flux of a commutating reactor. However, the commutating reactor is shunted by a resistor. At first sight, this seems to be a disadvantage because this requires more power of the transformer 65. However, this power is very small compared to the power of the mechanical rectifier. On the other hand, resistive shunting of the flux reversal circuit has the very great advantage of providing additional damping of the magnetic amplifier which reduces the possibility of instabilities and renders the control more linear. It should be noted that in many applications of magnetic amplifiers the output circuits are in fact shunted with resistors in order to render them more linear and more stable. In this case, the by-pass circuit introduces a resistive by-pass to the flux reversal circuit which is not necessarily a disadvantage.

In my copending application Serial No. 412,165 filed February 25, 1954, and now abandoned, I describe a method whereby two separate reactors may be replaced by a single reactor having two cores and a single winding. This novel construction may be utilized in the instant invention as seen in Figures 7a and 7b.

Figure 7a shows the reactors 11 and 13 as they are connected in Figure 2. These reactors have the main windings 21 and 30 respectively and the cores 23 and 32 respectively.

In Figure 7b in accordance with the construction set forth in above noted U.S. Patent No. 2,756,380, the two cores are arranged concentrically and have the common winding 21. Winding 21 therefore, also serves as the winding 30, this being indicated by placing number 30 in parentheses.

The current i_1 now flows through the common winding 21 and magnetizes both the cores 23 and 32. However, the core 32 should be magnetized only by the current i_2 which is the difference between the currents i_1 and i_3 . This can easily be compensated for by a negative winding 70 of the same number of turns as the winding 21. The current i_3 then demagnetizes the core 32 by the same amount as it did when flowing through the winding 21. It can be shown by more thorough analysis that the voltage and current conditions of these two arrangements of coils are absolutely identical and equivalent.

Figure 8a shows, in essence, the flux reversal circuit seen in Figure 2. This flux reversal circuit consists merely of the transformer 65 energizing the parallel circuits containing diodes 62 and 63 respectively, transductors 54 and 55 respectively, flux reversal windings 28 and 29 respectively, and the transformer 65 is then connected between the main power windings 28 and 29 and the function between the diodes 62 and 63.

In order to prevent reversal of the flux in the cores 32 and 33 of the auxiliary commutating reactors if they are connected according to Figure 7b, the windings 70 and 72 are also used to prevent the flux reversal current from affecting the two cores according to the compensation described in Figure 7b. This then results in the circuit connection of Figure 8b which is absolutely equivalent to the Figure 8a, except that it eliminates the flux reversal winding on the commutating reactors.

Figure 9 shows a complete three-phase double way rectifier using both the by-pass circuit and flux reversal circuit described heretofore. In Figure 9, A.-C. terminals 73, 74 and 75 are connected to energize the three-phase power transformer 76. Each phase is provided with commutating reactors 77 through 82 respectively, which are connected in series with mechanical rectifier contacts 83 through 88 respectively, and appropriate connections are made to the D.-C. terminals 90 and 91. In accordance with the construction of Figure 8b, flux reversal is provided by transductors 92 through 97, which work in

conjunction with the diodes 98 through 103. The operation of this flux reversal circuit is the same as described in Figure 6 for the circuit of Figure 2.

In addition to the flux reversal circuit, a by-pass circuit of the type shown in Figure 2 is provided and consists of the rectifier circuits 104 through 109 and the resistors 110 through 115.

It was seen in Figure 2 that power supplies for the flux reversal circuit and the by-pass circuit required the transformers 51 and 65. The transformer 51 of Figure 2 consists of a three winding transformer with the primary winding 50 and the secondary windings 47 and 48. Since windings 47 and 48 carry direct currents which are in opposition, the transformer core 49 is not magnetized by unidirectional current but the transformer is a true A.-C. transformer. Hence, it is possible to transform a pure A.-C. voltage that has been appearing between the terminals 52 and 53 into two direct current circuits without saturating the transformer core.

The transformer 65 is also a true transformer because it also feeds two diode circuits which are connected in opposition. Therefore, in the circuit of Figure 9, instead of having two transformers per phase, which for a three-phase system would require a total of six transformers, a single transformer 116 may be utilized. Transformer 116 consists of a primary winding 117 connected in polygon whereby the polygon connection serves to obtain a 15° phase shift from the main transformer 76. The secondary windings 118 are connected in three independent single phase windings, each having a single phase voltage displaced by 120° from the voltage in the adjacent windings. These transformer windings each correspond to a transformer winding such as the secondary winding of transformer 65 in Figure 2.

The windings 119 and 120 are again two groups of three single phase windings each being energized by the same primary winding 117. Hence, a single three phase transformer structure 116 serves to supply all of the power requirements for the by-pass and flux reversal circuits.

More specifically, the transformer 116 has five different windings on each leg. Two windings make up the windings of the primary winding 117, one being a long winding and the other being a short winding. The secondary, tertiary and quaternary windings 118, 119 and 120 each require one winding on the same leg. This is true for all three phases, the transformer then having three legs with five windings each. The secondary winding 118 feeding the flux reversal circuit has a voltage which is in the same phase relationship as shown in Figure 6. The tertiary winding 119 and the quaternary winding 120 feed the by-pass circuit with a voltage which is in phase with a voltage such as voltage e_{48} of Figure 5. These voltages are also in phase with the voltage shown to be provided by the transformer 116 in Figure 9. It should be noted that the flux reversal voltage of Figure 5 and the voltage required to drive the by-pass circuit of Figure 6 are not in phase but are 180° out of phase. This phasing of 180° , however, is easily obtained because the windings are open and can be connected in any way as is desired in the circuitry.

The control windings of transductors 92 through 97 are energized through the rheostat 121 and smoothing choke 122 and rectifier 123. D.-C. bias is applied to the cores of the main commutating reactor and auxiliary commutating reactors at the windings 124 through 129. These windings are in turn fed through the rheostat 130 and the choke 131 from the same rectifier 123. It should be noted that each of these pre-excitation windings has a small number of turns around both commutating reactor cores and an additional number of turns around the inner commutating reactor core which pertains to the auxiliary commutating reactor. This different magnetization affords compensation for the partial amount of the main commutating reactor magnetizing

current and the full magnetizing current of the auxiliary commutating reactor. This different compensation of magnetizing current is possible because in the main commutating reactor the magnetizing current varies between a minimum and maximum value and compensation is possible for the minimum value and no more. On the other hand, on the auxiliary commutating reactor compensation can be made for the full amount of the magnetizing current as was described in the discussion of Figure 5.

The novel circuitry set forth in Figure 9 has further structural advantages in the practical rectifier unit. That is, a minimum number of terminals are required for the auxiliary circuits inserted in closed tanks through which filtered oil is circulated and nitrogen under pressure is on top of the oil. Bushings which must carry the main current or auxiliary currents to the transformer tank are subjected to leaks, and, if they leak, the nitrogen under pressure expels the oil at a very great rate. The circuits under question, however, can provide complete flux reversal and compensation of the magnetizing current of each commutating reactor by adding only one auxiliary lead per commutating reactor. This leads to a system having only a few bushings for the transformer and compares very favorably with prior circuits which require up to ninety auxiliary bushings for one transformer tank.

Although I have described preferred embodiments of my invention, many variations and modifications will now be apparent to those skilled in the art and I prefer to be limited, therefore, not by the specific disclosure herein, but only by the appended claims.

I claim:

1. A by-pass circuit for an electrical contact; said electrical contact being movable to open and close an electrical circuit; said by-pass circuit comprising a saturable reactor connected in series with said contact and a rectifier means connected in parallel with said series connected saturable reactor and contact; said rectifier being connected in series with a voltage source and an impedance; said voltage source being connected to pass current through said rectifier before said contact is moved to open said electrical circuit to provide a low impedance path for current flow in said by-pass circuit; said rectifier being connected in a direction to block said current flow in said bypass circuit.

2. A by-pass circuit for an electrical contact; said electrical contact being movable to open and close an electrical circuit; said by-pass circuit comprising a saturable reactor connected in series with said contact and a rectifier means connected in parallel with said series connected saturable reactor and contact; said rectifier being connected in series with a voltage source and an impedance; said voltage source being connected to pass current through said rectifier before said contact is moved to open said electrical circuit to provide a low impedance path for current flow in said by-pass circuit; said rectifier being connected in a direction to block said current flow in said bypass circuit; the impedance of said by-pass circuit when said contact is open being substantially that of said impedance connected in series with said rectifier means.

3. A by-pass circuit for an electrical contact; said electrical contact being movable to open and close an electrical circuit; said by-pass circuit comprising a saturable reactor having a substantially negligible low magnetizing current connected in series with said contact and a rectifier means connected in parallel with said series connected saturable reactor and contact; said rectifier being connected to block the flow of current through said contact prior to contact opening; said rectifier being connected in series with a voltage source and an impedance; said voltage source being connected to pass current through said rectifier before said contact is moved to open said electrical circuit to provide a low impedance path for current flow in said by-pass circuit.

4. A by-pass circuit for an electrical contact; said

electrical contact being movable to open and close an electrical circuit; said by-pass circuit comprising a saturable reactor connected in series with said contact and a single phase bridge connected rectifier; the A.-C. terminals of said rectifier being connected in parallel with the series connection of said saturable reactor and contact; an alternating voltage source and a resistor; said alternating voltage source and said resistor being connected in series with the D.-C. terminals of said rectifier.

5. A by-pass circuit for an electrical contact; said electrical contact being movable to open and close an electrical circuit; said by-pass circuit comprising a saturable reactor connected in series with said contact and a single phase bridge connected rectifier; the A.-C. terminals of said rectifier being connected in parallel with the series connection of said saturable reactor and contact; an alternating voltage source and a resistor; said alternating voltage source and said resistor being connected in series with the D.-C. terminals of said rectifier; said alternating voltage source being connected to pass current through said rectifier before said contact is moved to open said electrical circuit to thereby provide a low impedance path for current flow in said by-pass circuit; the impedance of said by-pass circuit when said contact is open being substantially the resistance of said resistor.

6. A by-pass circuit for a contact connected in series with a commutating reactor; said contact being movable between an open and a closed position; said commutating reactor being constructed to provide a low current step within which said contact is disengaged; said by-pass circuit comprising an auxiliary commutating reactor having a magnetizing current substantially lower than the magnetizing current of said commutating reactor connected in series with said contact and a rectifier; said rectifier being connected in parallel with said series connected auxiliary commutating reactor and contact; said rectifier being connected in series with a voltage source and an impedance; said voltage source being connected to pass current through said rectifier before said contact is moved to open said electrical circuit to provide a low impedance path for current flow in said by-pass circuit.

7. A by-pass circuit for a contact connected in series with a commutating reactor; said contact being movable between an open and a closed position; said commutating reactor being constructed to provide a low current step within which said contact is disengaged; said by-pass circuit comprising an auxiliary commutating reactor connected in series with said contact and a single phase bridge connected rectifier; the A.-C. terminals of said rectifier being connected in parallel with the series connection of said auxiliary commutating reactor and contact; an alternating voltage source and a resistor; said alternating voltage source and said resistor being connected in series with the D.-C. terminals of said rectifier.

8. A by-pass circuit for a contact connected in series with a commutating reactor; said contact being movable between an open and a closed position; said commutating reactor being constructed to provide a low current step within which said contact is disengaged; said by-pass circuit comprising an auxiliary commutating reactor connected in series with said contact and a single phase bridge connected rectifier; the A.-C. terminals of said rectifier being connected in parallel with the series connection of said auxiliary commutating reactor and contact; an alternating voltage source and a resistor; said alternating voltage source and said resistor being connected in series with the D.-C. terminals of said rectifier; said alternating voltage source being connected to pass current through said rectifier before said contact is moved to open said electrical circuit to thereby provide a low impedance path for current flow in said by-pass circuit; the impedance of said by-pass circuit when said contact is open being substantially the resistance of said resistor.

9. In a contact converter for energizing a D.-C. load from an A.-C. source, said converter comprising the se-

ries connection of a commutating reactor, a pair of co-operating contacts being synchronously operated between an engaged and a disengaged position, said A.-C. source and said D.-C. load; a by-pass circuit; said by-pass circuit comprising an auxiliary commutating reactor having a magnetizing current substantially lower than the magnetizing current of said commutating reactor connected in series with said contact and a rectifier; said rectifier being connected to block the flow of current through said contact prior to contact opening; said rectifier being connected in parallel with said series connected auxiliary commutating reactor and contact; said rectifier being connected in series with a voltage source and an impedance; said voltage source being connected to pass current through said rectifier before said contact is moved to open said electrical circuit to provide a low impedance path for current flow in said by-pass circuit.

10. In a multi-phase contact converter for energizing a D.-C. load from a multi-phase A.-C. source, each phase of said converter comprising the series connection of a commutating reactor, a pair of co-operating contacts being synchronously operated between an engaged and a disengaged position, said A.-C. source and said D.-C. load; a by-pass circuit; said by-pass circuit comprising an auxiliary commutating reactor having a magnetizing current substantially lower than the magnetizing current of said commutating reactor connected in series with said contact and a rectifier; said rectifier being connected to block the flow of current through said contact prior to contact opening; said rectifier being connected in parallel with said series connected auxiliary commutating reactor and contact; said rectifier being connected in series with a voltage source and an impedance; said voltage source being connected to pass current through said rectifier before said contact is moved to open said electrical circuit to provide a low impedance path for current flow in said by-pass circuit; said rectifier being connected to block the flow of current through said contact prior to contact opening.

11. In a contact converter for energizing a D.-C. load from an A.-C. source, said converter comprising the series connection of a commutating reactor, a pair of co-operating contacts being synchronously operated between an engaged and a disengaged position, said A.-C. source and said D.-C. load; a by-pass circuit; said by-pass circuit comprising a saturable reactor connected in series with said contact and a single phase bridge connected rectifier; the A.-C. terminals of said rectifier being connected in parallel with the series connection of said saturable reactor and contact; an alternating voltage source and a resistor; said alternating voltage source and said resistor being connected in series with the D.-C. terminals of said rectifier; said rectifier being connected to block the flow of current through said contact prior to contact opening.

12. In a multi-phase converter for energizing a D.-C. load from a multi-phase A.-C. source, each phase of said converter comprising the series connection of a commutating reactor, a pair of co-operating contacts being synchronously operated between an engaged and a disengaged position, said A.-C. source and said D.-C. load; a by-pass circuit; said by-pass circuit comprising a saturable resistor connected in series with said contact and a single phase bridge connected rectifier; the A.-C. terminals of said rectifier being connected in parallel with the series connection of said saturable reactor and contact; an alternating voltage source and a resistor; said alternating voltage source and said resistor being connected in series with the D.-C. terminals of said rectifier; said rectifier being connected to block the flow of current through said contact prior to contact opening; said alternating voltage source being connected to pass current through said rectifier before said contact is moved to open said electrical circuit to thereby provide a low impedance path for current flow in said by-pass circuit; the impedance of

said by-pass circuit when said contact is open being substantially the resistance of said resistor.

13. A by-pass circuit for an electrical contact; said electrical contact being movable to open and close an electrical circuit; said by-pass circuit comprising a saturable reactor connected in series with said contact and a single phase bridge connected rectifier; the A.-C. terminals of said rectifier being connected in parallel with the series connection of said saturable reactor and contact; an alternating voltage source and a resistor; said alternating voltage source and said resistor being connected in series with the D.-C. terminals of said rectifier; said alternating voltage source being connected to pass current through said rectifier before said contact is moved to open said electrical circuit; the voltage drop across the A.-C. terminals of said rectifier bridge being the difference between a first voltage drop on first rectifier diodes of said bridge carrying by-pass circuit current and current due to said voltage source in the same direction and a second voltage drop on second rectifier diodes of said bridge carrying by-pass circuit current and current due to said voltage source in opposite directions.

14. A by-pass circuit for an electrical contact; said electrical contact being movable to open and close an electrical circuit; said by-pass circuit comprising a saturable reactor connected in series with said contact and a single phase bridge connected rectifier; the A.-C. terminals of said rectifier being connected in parallel with the series connection of said saturable reactor and contact; and alternating voltage source and a resistor; said alternating voltage source and said resistor being connected in series with the D.-C. terminals of said rectifier; said alternating voltage source being connected to pass current through said rectifier before said contact is moved to open said electrical circuit; the voltage drop across the A.-C. terminals of said rectifier bridge being the difference between a first voltage drop on first rectifier diodes of said bridge carrying by-pass circuit current and current due to said voltage source in the same direction and a second voltage drop on second rectifier diodes of said bridge carrying by-pass circuit current and current due to said voltage source in opposite directions; said first and second diodes of said rectifier bridge being constructed to make said first and second voltage drops substantially equal.

15. A by-pass circuit for a contact connected in series with a commutating reactor; said contact being movable between an open and a closed position; said commutating reactor being constructed to provide a low current step within which said contact is disengaged; said by-pass circuit comprising an auxiliary commutating reactor connected in series with said contact and a single phase bridge connected rectifier; the A.-C. terminals of said rectifier being connected in parallel with the series connection of said auxiliary commutating reactor and contact; an alternating voltage source and a resistor; said alternating voltage source and said resistor being connected in series with the D.-C. terminals of said rectifier; the voltage drop across the A.-C. terminals of said rectifier bridge being the difference between a first voltage drop on first rectifier diodes of said bridge carrying by-pass circuit current and current due to said voltage source in the same direction and a second voltage drop on second rectifier diodes of said bridge carrying by-pass circuit current and current due to said voltage source in opposite directions.

16. A by-pass circuit for a contact connected in series with a commutating reactor; said contact being movable between an open and a closed position; said commutating reactor being constructed to provide a low current step within which said contact is disengaged; said by-pass circuit comprising an auxiliary commutating reactor connected in series with said contact and a single phase bridge connected rectifier; the A.-C. terminals of said rectifier being connected in parallel with the series connection of said auxiliary commutating reactor and con-

tact; an alternating voltage source and a resistor; said alternating voltage source and said resistor being connected in series with the D.-C. terminals of said rectifier; the voltage drop across the A.-C. terminals of said rectifier bridge being the difference between a first voltage drop on first rectifier diodes of said bridge carrying by-pass circuit current and current due to said voltage source in the same direction and a second voltage drop on second rectifier diodes of said bridge carrying by-pass circuit current and current due to said voltage source in opposite directions; said first and second diodes of said rectifier bridge being constructed to make said first and second voltage drops substantially equal.

17. In a contact converter for energizing a D.-C. load from an A.-C. source, said converter comprising the series connection of a commutating reactor, a pair of cooperating contacts being synchronously operated between an engaged and a disengaged position, said A.-C. source and said D.-C. load; a by-pass circuit; said by-pass circuit comprising a saturable reactor connected in series with said contact and a single phase bridge connected rectifier; the A.-C. terminals of said rectifier being connected in parallel with the series connection of said saturable reactor and contact; an alternating voltage source and a resistor; said alternating voltage source and said resistor being connected in series with the D.-C. terminals of said rectifier; said rectifier being connected to block the flow of current through said contact prior to contact opening; the voltage drop across the A.-C. terminals of said rectifier bridge being the difference between a first voltage drop on first rectifier diodes of said bridge carrying by-pass circuit current and current due to said voltage source in opposite directions.

18. In a contact converter for energizing a D.-C. load from an A.-C. source, said converter comprising the series connection of a commutating reactor, a pair of cooperating contacts being synchronously operated between an engaged and a disengaged position, said A.-C. source and said D.-C. load; a by-pass circuit; said by-pass circuit comprising a saturable reactor connected in series with said contact and a single phase bridge connected rectifier; the A.-C. terminals of said rectifier being connected in

parallel with the series connection of said saturable reactor and contact; an alternating voltage source and a resistor; said alternating voltage source and said resistor being connected in series with the D.-C. terminals of said rectifier; said rectifier being connected to block the flow of current through said contact prior to contact opening; the voltage drop across the A.-C. terminals of said rectifier bridge being the difference between a first voltage drop on first rectifier diodes of said bridge carrying by-pass circuit current and current due to said voltage source in the same direction and a second voltage drop on second rectifier diodes of said bridge carrying by-pass circuit current and current due to said voltage source in opposite directions; said first and second diodes of said rectifier bridge being constructed to make said first and second voltage drops substantially equal.

19. In a multiphase system for exchanging energy between a multiphase A.-C. system and a D.-C. system, each phase of said multiphase A.-C. system being connected in series with a synchronously operated contact, a commutating reactor and said D.-C. system; a by-pass circuit for each of said contacts; each of said by-pass circuits comprising an auxiliary commutating reactor having an appreciably lower magnetizing current than the magnetizing current of said commutating reactor and a single phase rectifier bridge; the A.-C. terminals of said rectifier bridge being connected in parallel with the series connection of said auxiliary commutating reactor and contact; a transformer having a first and second secondary winding and a resistor connected in series with each of said first and second windings; said first winding and said first resistor being connected in series with the D.-C. terminals of said bridge rectifier of one of said multiphase systems; said second winding and said second resistor being connected in series with the D.-C. terminals of said bridge rectifier of another of said multiphase systems, the D.-C. ampere turns of said first and second secondary windings being oppositely directed with respect to one another.
